RESISTOR

Charles C. Whittaker, Pittsburgh, Pa., assignor to
Westinghouse Electric & Manufacturing Com-
pany, East Pittsburgh, Pa., a corporation of
Pennsylvania

Application May 20, 1942, Serial No. 443,697

16 Claims. (Cl. 201—63)

My invention relates, generally, to resistors, and it has reference in particular to enclosed resistors.

Generally stated, it is an object of my invention to provide an enclosed resistor which is simple and inexpensive to manufacture and is efficient and durable in operation.

More specifically, it is an object of my invention to provide an enclosed resistor having a resistance element supported within, and in spaced and insulated relation to a metal casing, and prevent the formation of moisture films between the terminals and the casing without requiring sealing of the casing.

It is also an object of my invention to provide for spacing a plurality of insulators supporting a resistance element in a casing.

Likewise, it is an important object of my invention to provide a resistor unit that is easy to assemble and is readily accessible for inspection.

An important object of my invention is to provide for supporting a resistance element within and in predetermined spaced relation to a metal casing having an integral cooling fin to dissipate the heat produced by the element.

Another object of my invention is to provide for integrating a metal resistor casing and members and cooling fin into a single unit by furnace brazing.

A further object of my invention is to provide for spacing a plurality of insulating supports which locate a resistance element within a casing without impeding the flow of heat from the element to the casing more than a minimum amount.

Yet another object of my invention is to provide a terminal construction for enclosed resistors wherein moisture traps are provided between the terminal and casing having ceramic creepage paths in series therewith.

Still another object of my invention is to provide a moistureproof terminal structure for an explosion-tested enclosed resistor.

It is an additional object of my invention to provide an improved explosion-tested enclosed resistor construction that is strong and durable and which is relatively easy and inexpensive to repair in the event of a failure.

Other objects will in part be obvious, and will in part appear hereinafter.

In practicing my invention, a helical cooling fin and relatively heavy tubular end members are furnace brazed to a relatively thin metal tubular casing. An elongated resistance element

is supported within the casing by means of relatively short tubular insulating supports positioned about the element at spaced intervals and maintained in such position by relatively thin elongated insulating spacers positioned between adjacent supports on one side of the element. Terminal members secured to the ends of the element project through ceramic bushings having annular pockets adjacent the terminal members and the end members separated by suitable creepage surfaces. Asbestos washers placed in the pockets absorb moisture and keep the interior of the casing relatively dry. The bushings are secured in the end members by means of snap rings.

For a more complete understanding of the nature, scope and objects of my invention, reference may be had to the following detailed description which should be read in connection with the accompanying drawing, in which:

Fig. 1 is a partly sectioned side elevational view, of an enclosed resistor embodying the principal features of the invention;

Fig. 2 is a partly sectioned side elevational view of a modified form of an enclosed resistor;

Fig. 3 is a cross-sectional view taken along the line III—III of Fig. 1;

Fig. 4 is a reduced plan view of a resistor construction embodying the invention;

Fig. 5 is a left-hand end elevational view, broken out in part, of the resistor construction shown in Fig. 4;

Fig. 6 is a right-hand end elevational view of the resistor structure shown in Fig. 4;

Fig. 7 is an end elevational view of the right-hand or rear frame member of the resistor structure of Fig. 4; and

Fig. 8 is an end elevational view of the left-hand or front frame member of the resistor structure shown in Fig. 4.

Referring to Figs. 1 and 3, the reference numeral 10 may denote, generally, an explosion-tested enclosed resistor such as is acceptable for use in gaseous atmospheres where the atmosphere may be ignited by a spark or overheated portion of the resistor, comprising a resistance element 12 provided with a casing 14 and projecting end terminals 15.

The resistance element 12 may be of any suitable construction, comprising, for example, an elongated helix of a plurality of turns of a relatively small resistance wire 16 such as shown in Figs. 1 and 3. The element may also comprise a substantially straight rod 17 without depart-

ing from the invention, as shown in Fig. 2. Any of the well known materials may be used for the resistance element, such as, for example, one of the nickel-chromium alloys which has a relatively high resistance and a relatively high mechanical strength at high temperatures.

The casing 14 may not only serve to enclose and protect the resistor, but may serve also as a radiator therefor, and may, as shown in Figs. 1 and 3, comprise a suitable length of metal tubing 18, of seamless steel or the like. In order to secure the maximum radiation from the resistance element with the minimum spacing, means such as the cooling fin 20 may be provided. The fin 20 may comprise a helix of soft steel ribbon wound on edge, positioned about the tubing 18 and stretched to the proper length.

Means such as the end members 22 may be connected to the tubing 18 adjacent the ends. The end members 22 may, for example, comprise short lengths of a relatively heavy steel tubing having inner diameters slightly less than the outer diameter of the tubing 18, and recessed adjacent one end to provide peripheral shoulders 23, so that they may be fitted over the end portions of the tubing 18, which may abut the shoulders 23. The inner surfaces of the end members may be suitably shaped at the other ends to provide peripheral shoulders 24 intermediate the ends and peripheral grooves 25 adjacent the outer ends.

The tubing 18, cooling fin 20 and the end members 22 may be assembled in any suitable manner, such as, by tack welding the cooling fin 20 to the end members by welds 26, and tack welding the end portions of the fin to the tubing 18 by welds 27. The assembly of the tubing, end members and cooling fin may then be integrated by furnace brazing, through wrapping a suitable length of copper wire about the tubing between the turns of the cooling fin and heating the whole in a hydrogen atmosphere furnace to cause the copper to flow and form a fillet 28 completely integrating the end members, tubing and cooling fin.

In order to provide for positioning the resistance element 12 within the casing 14, suitable means such as the insulating supports 30 may be provided at spaced intervals along the element. The supports 30 may comprise buttons, rings or relatively short refractory ceramic tubes having openings 31 therethrough and capable of withstanding heat shock. The outer diameter may be slightly less than the inner diameter of the tubing 18, and the diameter of the opening 31 may be slightly larger than the outer diameter of the resistance element. The supports 30 may be slipped onto the element 12 and spacing of the supports may be secured by positioning elongated ceramic spacers 32 between the adjacent supports. The spacers 32 may comprise ceramic tubes of such an outside diameter that they may be relatively loosely positioned between the resistance element 12 and the tubing 18 on one side of the element, where they are retained by the tubing, so as to impede the flow of heat therefrom as little as possible.

The terminals may be of any construction which provides a good electrical connection with the resistance element 12 and sufficient self-cooling to maintain the outer ends at a safe temperature relative to the surrounding gaseous atmosphere. Where a helix of a relatively small wire 16 is used, the terminals are preferably of a rela-

tively high conductivity and may comprise a length of copper rod having a flange 34 adjacent the inner end with a longitudinal opening 35 to receive a straightened portion of the wire 16. The wire may be secured to the terminal at the outer end by brazing 36, thus securing a good electrical connection with a minimum of heat conduction from the element to the terminal.

In order to support the terminals 15 and prevent the entrance of moisture into the casing 14, which inevitably results in a reduction of the insulating value of the insulating supports, means such as the terminal assembly denoted, generally, by the numeral 38 may be provided at the ends of the resistor. For example, a pair of ceramic buttons or discs 39 having central openings 40 to receive the terminals 15 may be positioned within the end members 22. These discs may be provided with peripheral recesses 41 and 42 adjacent the inner and outer edges. An additional ceramic member 43 may be provided having a peripheral rib 44 adjacent one end, defining a peripheral end recess 45 corresponding to the outer peripheral recess 42 of the ceramic discs 39, and a peripheral shoulder 46 intermediate the ends. The ceramic discs and additional ceramic member are preferably of a ceramic material having a low moisture absorption factor, such as lava, or one of the silicates, such as aluminum magnesium silicate.

By positioning the discs 39 within the end member 22 in opposed relation, with the inner one abutting the shoulder 46 of the end member 22, the two inner recesses 41 are juxtaposed, and cooperate to provide a substantially closed inner chamber about the terminal 15 for receiving a moisture absorbing material to prevent the passage of moisture along the terminal member 15 into the interior of the casing. The outer peripheral recesses 42 of the outer discs 39 and 45 of the insulating member 43 are likewise juxtaposed and cooperate to provide an outer annular chamber adjacent the inner surface of the end member for receiving a moisture absorbent material to prevent the passage of moisture along the inner surface of the end member. The chambers thus formed may be filled with any suitable moisture absorbent material, such as, for example, the asbestos discs 47 and 48. Moisture traps are thus provided at the inner and outer surface of the insulation supporting the terminal member 15, which are separated from each other, and have ceramic creepage surfaces 49 and 50 in series therewith between the terminal member and the end member. Moisture absorbed by the discs 47 and 48 cannot therefore bridge between the end member and the terminal to cause a breakdown.

The resistor may be assembled by stringing the insulating supports 30 on the resistance element 12 and inserting them in casing 14, placing the spacers 32 between adjacent supports in turn. The ceramic discs 39, additional ceramic members and asbestos discs may then be assembled on the terminals 15, where they may be retained by means such as the turns of wire 53, which may be placed in grooves 54 about the terminals and secured by twisting the ends together as indicated. The terminal assembly may be dropped over the straightened end portions of the wire 16 into the end members and secured by means such as the snap rings 56, which may be positioned in the grooves 25 adjacent the outer ends of the end members to engage the peripheral shoulder portions 46 of the insulating members 43. The

wire 16 may then be cut off to the proper length and secured to the terminals 15 by brazing 38.

The resistor 67 shown in Fig. 2 is substantially identical with the resistor shown in Fig. 1, so that, in general, details of the construction thereof need no further explanation. Since the resistance element 17 comprises a relatively heavy conductor, the insulating supports 30 of the resistor 67 may be spaced further apart. Accordingly, the spacers 58 may be longer than the spacers 32 of the resistor 10. Instead of providing an opening throughout the length of the terminal member 59 to accommodate the resistance element 17, only a relatively shallow recess 60 need be provided at the inner end of the terminal member 59 for securing the end portion of the resistance element 17 therein by brazing or the like, since a good connection may be effected therebetween which remains unaffected by the heat developed in the resistance element 17. Since the contact between the element 17 and the terminal 59 is relatively limited, and little or no heat is developed in the terminal 59, it may be kept sufficiently cool for relatively high operating temperatures of the element. The terminal member 59 may be supported in the end member 27 by a terminal support structure 38 substantially the same as described in connection with the resistor of Fig. 1.

Referring to Figs. 4 through 8, the reference numeral 64 may denote, generally, a resistor construction wherein a resistor unit 65 comprising a pair of resistors 66 of a type such as shown in Figs. 1 and 2, may be supported in spaced frame members 67 and 70 which may be connected by supports 71.

For the purpose of providing a resistor unit having readily accessible terminals, for application where one end of the unit is relatively inaccessible, such as, for example, in some applications on mining locomotives, the terminals at the rear end of the resistors may be connected by means of a conductor 72, so that both of the terminals to which exterior connections are to be made are at the other end of the unit. Means such as the yokes or connectors 73 and 74 may be provided adjacent the ends of the resistors to maintain them in spaced relation and provide a substantially integral resistor unit. The connector 73 may, for example, comprise a substantially figure 8 shape having spaced openings 76 and 77 to receive the end members 22 of the resistors. The connector 74 may be of any suitable shape comprising, for example, a rectangular plate having spaced openings 78 and 79 to receive the opposite end members of the resistors.

In order to provide a substantially integral unit having relatively low replacement cost, the connectors 73 and 74 may be permanently connected to the end members 22 of one resistor by means of welds 80, and may be connected to the end members of the other resistor more or less temporarily by means of relatively frangible tack welds 81 which may be more or less easily broken in the case it is found necessary to replace one or the other of the resistors. A relatively strong and rigid construction is thus provided, and yet in case of failure of either of the resistors, only one or the other need be replaced and not both, which would be the case if both resistors were permanently connected to the connectors.

The right-hand or front frame member 70 may be provided with a pair of spaced openings 82 connected by a restricted opening 83 sufficiently large to permit the resistors and the con-

nectors 73 to pass therethrough, as shown in Fig. 8. The left-hand or rear frame member 87 may be provided with a pair of spaced openings 84, connected by a restricted opening 85 sufficiently large to permit the terminal conductor 72 to pass therethrough and to receive the end members 22. To assist in inserting the resistor unit 65 in the frame openings, means such as the rod 87 may be provided, extending between the front and rear frame members 70 and 67, and positioned in openings 88 and 89 therein intermediate and slightly below the spaced frame openings 82 and 84 therein. The rod 87 may be so positioned relative to the frame openings that the connector 73 may rest thereon as the resistor unit is being inserted in the openings whereby the rear end members 22 will be guided into the spaced opening 84 in the rear frame member. Suitable means may be provided for securing the resistor unit relative to the frame members, such as, for example, the nut 90, which may be positioned on the front end of the rod 87.

From the above description and the accompanying drawing, it will be apparent that I have provided in a simple and inexpensive manner for supporting a resistance element within a metal casing. Efficient radiation of heat generated by the resistance element is effected by providing a relatively unobstructed path between the resistance element and the metal casing, and providing the maximum cooling arrangement for the casing by means of a helical fin integrally connected to the casing throughout its length. The entrance of moisture within the casing, when the resistor is operating in relatively damp locations, through the breathing action thereof as the air in the casing expands and contracts, is effectively prevented by means of the improved terminal structure I have provided. Resistors embodying the features of my invention have been successfully operated and tested by heating the resistors to a maximum operating temperature and draping the terminal ends with wet rags and rapidly cooling the whole resistor. Subsequently, while in a wet condition the resistors withstood from 3,800 to 4,400 volts before breaking down between the resistance element and the casing. After slightly heating the resistors they withstood 5,000 volts safely, thus indicating a satisfactory control of moisture leakage which heretofore caused failure in other designs of resistors used in locations where a relatively high moisture content is found.

Since certain changes may be made in the above description, and different embodiments of the invention may be made without departing from the spirit thereof, it is intended that all the matter contained in the above description and shown in the accompanying drawing shall be considered as illustrative, and not in a limiting sense.

I claim as my invention:

1. A resistor comprising, an elongated resistance element, a plurality of relatively thin insulating supports positioned substantially symmetrically about the element at spaced intervals at least four times the thickness of the supports, a relatively narrow insulating spacer loosely positioned between adjacent supports, and a metal casing symmetrically positioned about the element supports and spacers.

2. The combination in an enclosed resistor, of an elongated resistance element, a metallic casing positioned about the element, insulating supports positioned between the element and casing at spaced intervals, and an elongated insulat-

ing spacer positioned between adjacent supports to one side of the element and in engagement with the inner surface of the casing so as to be retained between said supports and on one side only of the resistance element by the casing.

3. A resistor comprising, an elongated resistance element, insulating supports positioned about the element at spaced intervals, a relatively thin-walled metal tube positioned about the element and supports having relatively thick-walled metallic tubular end members secured thereto, and a terminal member secured to each end of the resistance element supported by and in insulated relation to each end member by insulating means positioned in the tubular end member.

4. A resistor unit comprising, an elongated resistance element, a plurality of refractory supports positioned substantially concentrically about the element at spaced intervals, a separate elongated refractory spacer freely positioned between adjacent supports and located only on one side of the element, and a casing enclosing the element, supports and spacers.

5. The combination in a resistor, of an elongated resistance element, a plurality of rings of refractory material positioned about the element at spaced intervals, and substantially concentrically therewith, an elongated tubular refractory spacer loosely positioned eccentrically of the element so as to float between adjacent rings and to one side of the element, a metal tube positioned about the element, rings and spacers, and terminal members connected to the element projecting from the ends of the tube.

6. A resistor comprising, an elongated resistance element, a tubular casing positioned about the element, insulating means supporting the element in spaced relation within the tube, a terminal member connected to one end of the resistance element, and means insulating the terminal member from the tube including a plurality of ceramic discs having central openings to receive the terminal member and spaced recesses adjacent the inner and outer edges contiguous with the terminal member and tube, respectively, containing a moisture absorbent material.

7. An enclosed resistor comprising, an elongated resistance element, a plurality of refractory supports positioned along the element, an elongated spacer positioned between adjacent supports on one side of the element, a metal tube positioned about the element, supports and spacers, and means including a plurality of refractory discs having central recesses on one side and projecting central bosses on the other positioned in opposed relation to define inner and outer peripheral recesses in spaced relation to receive a moisture absorbent material.

8. The combination with a resistance element positioned within a casing and having an end terminal, of a plurality of ceramic discs positioned in opposed relation having central recesses and bosses on opposite sides defining inner and outer peripheral recesses adjacent the terminal and casing separated by ceramic leakage surfaces, and a plurality of asbestos discs positioned in the recesses against the terminal and tube.

9. An enclosed resistor comprising, an elongated metal casing, a resistance element positioned within the casing, spaced supports separating the element from the casing, a terminal member connected to the element, and a terminal support positioned about the terminal member within the end of the tube including a plurality

of ceramic discs having central openings to receive the terminal member and inner and outer peripheral recesses filled with a moisture absorbent material, said inner and outer recesses being separated from each other by continuous rib portions on the discs.

10. A terminal support for mounting a terminal member in a tubular container comprising, a plurality of ceramic discs having central openings for the terminal member and central recesses and projections on opposite sides positioned in opposed relation to define inner and outer peripheral recesses separated by ceramic creepage surfaces, plurality of asbestos discs positioned in the recesses to engage the terminal member and the container, and means to secure the ceramic discs in the container.

11. A resistor unit for mounting in a frame comprising, a pair of elongated resistance units having metallic casings, means comprising a pair of connectors secured to the casings adjacent the ends to mechanically connect the casings and position them in spaced relation, a pair of spaced frame members having openings to receive the units and at least one of the connectors, and means securing one of the connecting means to one of the frame members to secure the resistor unit relative to the frame.

12. A resistor structure comprising, a pair of elongated resistor units having metallic casings with terminals projecting from the ends, separate connecting members having openings to receive the ends of the casings positioned adjacent the ends thereof and welded thereto for mechanically connecting the casings to position them in spaced relation, and a terminal connector bridging the terminals at one end of the units.

13. A unit resistor comprising, a pair of elongated resistance elements positioned in metal casings with end terminals projecting therefrom, connectors rigidly attached to only one of the casings adjacent each end and having an opening spaced from said one casing to receive the other casing, frangible means mechanically connecting the other casing to the connectors so as to provide for readily separating the casings in the event of failure of one element, and a terminal connector connecting the terminals at one end.

14. A resistor structure comprising, a pair of resistor units having resistance elements supported within metal casings with end terminals projecting therefrom, connectors positioned adjacent each of the ends of the casings mechanically secured to the casings to maintain them in spaced relation, front and rear frame members positioned in spaced relation having openings to receive the casings and at least one of the connectors, and means including a tie rod extending between the frame members positioned to engage the connectors at the leading end of the units when the leading end is inserted through the opening in the front frame member to guide the leading end of the units into the opening in the rear frame member.

15. An enclosed resistor comprising, an elongated resistance element, a tubular metal casing positioned about the element, insulating supports spaced within the casing to support the element, a tubular end member secured about an end of the casing, a terminal connected to the element projecting through the end member, means including a plurality of refractory discs having central openings to receive the terminal and inner and outer annular recesses adjacent the ter-

minal and end member, moisture absorbent means positioned in the recesses, and retaining means attached to the terminal and end member to engage one of the refractory discs.

16. A resistor comprising, a pair of resistor units having resistance elements enclosed in tubular metal casings with terminals projecting from each of the ends, a pair of connectors mechanically connecting the casings adjacent each of the ends to secure the casings in fixed relation to each other, a terminal conductor connecting the terminals of the units at one end, spaced front and rear frame members having aligned

openings to receive the casings, the opening in one of the frame members being so shaped as to receive one of the connectors, and a tie rod for connecting the front connector relative to the frame members extending between the frame members intermediate the casings positioned to engage the connector at the leading end of the units so as to support said end of the units when said end is inserted in the opening in the front frame member to guide it into the opening in the rear frame member.

CHARLES C. WHITTAKER.
